(57) **CLAIM**

The ornamental design for a handle for cookware, as shown and described.

DESCRIPTION

FIG. 1 is a perspective view of a handle for cookware, showing my new design;

FIG. 2 is a right side view thereof; the left side view being the mirror image thereof;

FIG. 3 is a top view thereof;

FIG. 4 is a bottom view thereof;

FIG. 5 is a front view thereof; and,

FIG. 6 is a rear view thereof.

The broken lines in FIGS. 1-6 illustrate portions of a handle for cookware and form no part of the claimed design.
